P. A. STEDMAN

SUPPORTING DEVICE FOR MANIPULATING TOOLS

Filed Oct. 21, 1927

Inventor:
Percy Arthur Stedman
By Alfred H. Smith
his Atty.

UNITED STATES PATENT OFFICE.

PERCY ARTHUR STEEDMAN, OF BOMBAY, INDIA.

SUPPORTING DEVICE FOR MANIPULATING TOOLS.

Application filed October 21, 1927, Serial No. 227,696, and in Great Britain March 14, 1927.

This invention relates to a supporting device for manipulating tools, particularly portable machine tools which are operated by pneumatic, hydraulic and electric power.

- 5 The heavier classes of tools for drilling, riveting, punching, welding and other purposes have usually hitherto been held in the hand during manipulation which involves considerable physical exertion on the part 10 of the operator, and interferes with accurate work, especially when the tool has to be used in various positions.

An important object of the invention is to provide a portable device which shall not 15 only carry the tool, but will facilitate its easy manipulation in various positions without any appreciable weight or jarring on the hand of the operator who will, consequently, be free to use his skill and judgment without any physical strain or exertion due to bearing the weight of the tool.

Another object is to provide that the tool 20 can be readily moved into various positions of altitude and azimuth about a support which is itself readily movable from place to place, the tool being also adjustable into various positions on the device in whatever position of adjustment the latter may be situated.

30 According to an important feature of the invention there is provided the combination of a support, a telescopic extensible arm that is pivotally mounted between its ends on said support and has a slidable section 35 arranged to carry a tool at one side of the support, a balance weight so carried by the arm at the other side of the support as to be movable towards and away from the support, and means so operatively connecting 40 the balance weight with said slidable section as automatically to cause the weight and said section to approach and recede from said support in unison.

The invention consists in the construction, arrangement and combination of parts 45 described hereinafter and pointed out in the claims.

One embodiment of the invention is diagrammatically illustrated in perspective by 50 way of example in the accompanying drawing.

Referring to the drawing, a wheeled telescopic tripod stand comprises a two-part hollow tubular standard A, C, whereof the 55 upper part C is journalled in the lower part

at B, and a stem D which may be tubular, is adjustable vertically by means of a clamp C¹ provided on the part C. The stem D is thus free to rotate in the standard A, C, and carries a U-shaped bracket E at its upper end, to which is pivoted the telescopic extensible arm aforesaid. This arm comprises a tubular section H pivoted in the bracket E to rock about a horizontal axis, and a slidable section J which may also be a tube. Attached to the free end of the section J is a bracket M constituting a tool-holder, in which a tool O is mounted to swing.

The end of the pivoted section H at the side of the stand remote from the tool-holder slidably carries a balance weight T which is proportioned to the weight of the tool and tool-holder to be used. A collar U is rotatable on a sleeve attached to the weight T, and a collar K is rotatable on a sleeve attached to the bracket M, and these collars which are both rotatable about the longitudinal axis of the telescopic arm H, J, are connected respectively by means of pivoted links S, R, to the opposite ends of equalizing levers G, one at each side of the bracket E. These levers G are pivoted to rock about the same horizontal axis as the extensible arm H, J, and the movements of this arm in space do not alter the relation of the tool-holder M and the counterpoise T. On the other hand, if the section J is moved into or out of the section H, the weight T will also be moved in corresponding directions by means of the links R, S, and the levers G, and will thereby balance the tool O in its new position. The collar K allows the section J to rotate about its own longitudinal axis together with the tool-holder M and the tool O, without affecting the angular position of the links R in relation to the levers G, and consequently without shifting the weight T along its support.

It will be seen that tools of all kinds and various sizes can be placed in various positions, their weight being balanced by the counterpoise, thus relieving the operator from the exertion and work of carrying and supporting the tool in position, and enabling him to perform the work with skill and accuracy. By the use of the device according to the present invention, the tool can be used in a vertical, horizontal, radial and angular position, and in intermediate positions as in-

dicated by the arrows, and it is only when the distance between the point of support of the tool and the horizontal pivotal axis of the extensible arm varies, and with it the 5 distribution of weight about that axis, that the counterpoise T is shifted; in other positions, the balance of the tool is not upset, and hence the counterpoise mechanism is not called into operation. The device according 10 to the invention may be used with various kinds of tools such as are required in large factories and machine shops, as well as for lighter work. It can not only be readily run along the floor from one part of a 15 shop to another, but also readily adjusted in height to suit the work in hand.

I claim:

1. In a device of the character described, the combination of a support, a telescopic extensible arm that is pivotally mounted between its ends on said support and has a 20 slidable section arranged to carry a tool at one side of the support, a balance weight so carried by the arm at the other side of the support as to be movable towards and away from the support, and means so operatively connecting the balance weight with said slidable section as automatically to cause the weight and said section to approach and 25 recede from said support in unison.

2. In a device of the character described, the combination of a support, a telescopic extensible arm that is pivotally mounted between its ends on said support and has a slidable section arranged to carry a tool at one 30 side of the support, a balance weight so carried by the arm at the other side of the support as to be movable towards and away from the support, and a linkage pivotally mounted 35 on said support and so operatively connecting the balance weight with said slidable section as automatically to cause the weight and said section to approach and recede from said support in unison.

3. In a device of the character described, the combination of a support, a telescopic extensible arm that is pivotally mounted between its ends on said support and has a slidable section arranged to carry a tool at one 40 side of the support, a balance weight so carried by the arm at the other side of the support as to be movable towards and away from the support, and a linkage pivotally mounted 45 on said support coaxially with said arm, which linkage so operatively connects the balance weight with said slidable section as automatically to cause the weight and said section to approach and recede from said support in unison.

4. In a device of the character described, the combination of a support, a telescopic extensible arm that is pivotally mounted between its ends on said support and has a slidable section arranged to carry a tool at one side 50 of the support, a balance weight so carried

by the arm at the other side of the support as to be movable towards and away from the support, and a linkage comprising a double-ended lever mounted to rock about the axis of pivoting of said arm, a link connecting one arm of said lever with said slidable section, and a second link connecting the other arm of said lever with said weight, the ratio of the lengths of which lever arms is equal to the ratio of the distances between the said 70 pivotal axis and the points of connection of their respective links to the extensible arm.

5. In a device of the character described, the combination of a support that is adjustable in height, a telescopic extensible arm 80 that is mounted to swivel between its ends on said adjustable support and has a slidable section arranged to carry a tool at one side of the support, a balance weight so carried by the arm at the other side of the support as to be movable towards and away from the support, and means so operatively connecting the balance weight with said slidable section as automatically to cause the weight and said section to approach and recede from said support in unison in various 85 positions of adjustment of the support.

6. In a device of the character described, the combination of a telescopic support, a telescopic beam that is pivotally mounted 90 between its ends on said support and has a slidable section arranged to carry a tool at one side of the support, a balance weight so carried by the beam at the other side of the support as to be movable towards and away from the support, and means so operatively connecting the balance weight with said slidable section as automatically to cause the weight and said section to approach and recede from said support in unison.

7. In a device of the character described, the combination of a support, an extensible arm that is pivotally mounted between its ends to swivel on said support and is arranged to carry a tool at one side of the support, a counterpoise for the tool so carried by the arm at the other side of the support as to be movable towards and away from the support, and means so operatively connecting the counterpoise with the tool-carrying end of the arm as automatically to cause the counterpoise and said end of the arm to approach and recede from said support in unison.

8. In a device of the character described, the combination of a wheeled support, a telescopic extensible arm that is pivotally mounted between its ends on said support and has a slidable section arranged to carry a tool at one side of the support, a balance weight so carried by the arm at the other side of the support as to be movable towards and away from the support, and means so operatively connecting the balance weight with said slidable section as automatically

to cause the weight and said section to approach and recede from said support in unison.

9. In a device of the character described, 5 the combination of a support, a telescopic extensible arm that is pivotally mounted between its ends to swivel on said support and has a slidable section arranged to carry a tool at one side of the support, a balance 10 weight so carried by the arm at the other side of the support as to be movable towards and away from the support, a tool-holder so carried by said slidable section as to be rotatable about the longitudinal axis 15 thereof, a collar on said slidable section, which collar is held against movement along but is rotatable about said longitudinal axis, and a linkage that is pivotally mounted on said support, and is pivotally 20 connected to said collar and said weight, and is arranged to cause the weight and said tool-holder to approach and recede from said support in unison.

10. In a device of the character described, 25 the combination of a telescopic support in

the form of a wheeled tripod, a telescopic extensible arm comprising at least two sections, whereof one is pivotally mounted to swivel on said support and extends to one side thereof, and the other constituting a 30 slidable section extends towards the other side of the support, a balance weight slidable along the pivoted section, a tool-holder carried by the free end of said slidable section, a collar that is associated with said tool- 35 holder and is held against movement along but is rotatable about the longitudinal axis of said slidable section, linkage comprising a double-ended lever mounted to rock about the axis of pivoting of the pivoted section, a 40 link pivotally connecting one arm of said lever with said collar, and a second link pivotally connecting the other arm of said lever with said weight, the ratio of the lengths of which lever arms is equal to the ratio of the 45 distances between the said pivotal axis and the points of connection of their respective links to the extensible arm.

In testimony whereof I affix my signature.

PERCY ARTHUR STEDMAN.
